UNITED STATES PATENT OFFICE.

HOLMAN L. SELL, OF LITTLESTOWN, PENNSYLVANIA.

CANNED CORN SHAKER.

Application filed January 31, 1927. Serial No. 164,980.

This invention relates to a device for agitating the contents of cans, the device being more particularly designed for the treatment of canned corn, the general object of the invention being to provide means for giving a chute, through which the cans are passing, a shaking motion so as to agitate the contents of the cans and thus mix the liquids with the solids.

Another object of the invention is to so arrange the chute that the cans will pass through the same under the action of gravity and to provide means for regulating the speed at which the cans pass through the chute.

Another object of the invention is to provide power means for shaking the chute and for operating the speed regulating means.

This invention also consists in certain other features of construction and in the combination and arrangement of the several parts, to be hereinafter fully described, illustrated in the accompanying drawings and specifically pointed out in the appended claims.

In describing my invention in detail, reference will be had to the accompanying drawings wherein like characters denote like or corresponding parts throughout the several views, and in which:

Figure 1 is a side view of the device.

Figure 2 is a plan view thereof.

Figure 3 is a section on line 3—3 of Figure 2.

Figure 4 is a view of the rear end of the device.

Figure 5 is a plan view showing the chute at one limit of its movement, this view also showing the pivotal parts of the chute.

Figure 6 is a fragmentary view showing the chute in its other limit of movement.

Figure 7 is a section on line 7—7 of Figure 1.

Figure 8 is a section on line 8—8 of Figure 7.

In these views, 1 indicates a frame or table on which are placed the bearing posts 2 for the shaft 3 to which is attached the large pulley 4, the small pulley 5 and the cranks 6, the cranks being arranged at the end of the shaft. A belt 7 passes over the large pulley 4 and over a small pulley 8 which is connected with the shaft of the motor 9.

A pair of channel bars 10 is supported by the frame and these bars slope downwardly

from the front toward the rear. Transverse guides 11 are supported by these bars and a shoe 12 is slidably supported in each pair of guides. A connecting rod 13 connects each shoe with one of the cranks 6 so that the shoes are reciprocated when the shaft 3 is rotated from the motor. A sectional chute has its central portion 14 fastened to the shoes so that this portion is moved laterally by the reciprocatory movement of the shoes, the chute being composed of two angle bars spaced apart to receive a can, such as A, between them, the can being placed on its side so that it will roll through the chute under the action of gravity. The end sections 15 of the chute are each pivoted to the bars 10 by the pivot post 16 being supported by the cross pieces 17 carried respectively by the bars 10 and the bars forming the end sections of the chute. A small channel-shaped member 18 is fastened to each end of the central section of the chute and has its outer end flaring to receive the inner end of the end section so that when the middle section is reciprocated laterally, these members 18 will cause the end sections to rock on their pivots, as shown in Figures 5 and 6.

The cans are introduced into the front end section from an inclined chute 19, the lower end of which is supported from the frame 1 by the braces 20.

Bars 21 are supported by parts of the frame over the chute and these bars are parallel with the chute. Their ends support the pintles of the rollers 22 over which the endless belt 23 passes. One of these rollers is connected to a shaft 24 journaled in the frame through means of the gears 25 and 26. The said shaft has a pulley 26 thereon over which passes a belt 27 which also passes over the pulley 5 on the shaft 3. A belt tightener, shown generally at 28, is provided for this belt. Thus the belt 23 will be driven from the motor through means of the shaft 3.

A plurality of downwardly extending arms 29 is pivoted between the bars 21, these arms being arranged in pairs and carry at their lower ends the rollers 30 which engage the upper face of the lower reach of the belt 23 and thus presses it upon the cans passing through the chute. As these arms and their rollers have considerable weight, they will force the belt against the cans with considerable pressure and thus act to check the speed of the cans passing through the chute so that

by regulating the speed at which the belt 23 travels, the cans can be caused to pass down the chute at any desired speed. The arms 29 are limited in their downward movement by the stop pins 31 carried by the bars 21.

From the foregoing, it will be seen that the cans will pass down the chute under the action of gravity and their speed of travel 10 can be regulated by the traveling belt 23, so that they will remain in the shaker part of the chute the desired length of time. The central section of the chute is reciprocated laterally by the reciprocatory movement of 15 the shoes imparted to them by the crank means so that the contents of the cans are agitated and thus the solids will be thoroughly mixed with the liquids. While the invention is mainly designed for use with 20 canned corn, it is, of course, to be understood that it can be used with other canned goods.

It is thought from the foregoing description that the advantages and novel features of my invention will be readily apparent.

25 I desire it to be understood that I may make changes in the construction and in the combination and arrangement of the several parts, provided that such changes fall within the scope of the appended claims.

30 What I claim is:—

1. An apparatus of the class described comprising a supporting frame, a gravity chute therein composed of a central portion and a pair of end portions, means for pivoting the end portions to the frame, means for moving the middle portion laterally in a reciprocatory manner, means for causing the end portions to rock under the reciprocatory movement of the middle portion so that the cans from the end portions can pass upon the central portion and can pass from the central portion to the lower end portion, means for controlling the speed of the cans passing through the chute, such means comprising an endless belt, rollers over which the belt passes, means for rotating the roll-

ers and weighted means for holding portions of the belt in engagement with the cans.

2. An apparatus of the class described 50 comprising a supporting frame, a gravity chute therein composed of a central portion and a pair of end portions, means for pivoting the end portions to the frame, means for moving the middle portion laterally in a reciprocatory manner, means for causing the end portions to rock under the reciprocatory movement of the middle portion so that the cans from the end portions can pass upon the central portion and can pass from the 55 central portion to the lower end portion, means for controlling the speed of the cans passing through the chute, such means comprising an endless belt, rollers over which the belt passes, means for rotating the rollers, arms pivoted to a part of the frame and rollers on the arms engaging portions of the belt for pressing the same against the cans.

3. An apparatus of the class described 60 comprising a supporting frame, inclined bars on the frame, lateral guideways supported by the bars, a shoe slidably arranged in each guideway, a shaft journaled in the frame and having cranks thereon, connecting rods connecting the cranks with the 65 shoes, means for rotating the shaft, a sectional trough having its central section fastened to the shoes, means for pivoting the end portions to the frame, means at the ends of the central section engaging the end sections for causing the end sections to rock when the central section is moved, an endless belt, rollers supporting the same, means for supporting the rollers from the frame with the lower reach of the belt in engagement with the cans in the chute, means for rotating one of the rollers from the shaft and means for applying pressure to the 70 lower reach of the belt to press it upon the cans.

75 In testimony whereof I affix my signature.

HOLMAN L. SELL.
